UNITED STATES PATENT OFFICE.

MARCEL ANDRÉ JULLIEN, OF PARIS, FRANCE.

MAKING OF SHEET COPPER ELECTROLYTICALLY.

Application filed November 4, 1924. Serial No. 747,811.

To all whom it may concern:

Be it known that I, MARCEL ANDRÉ JULLIEN, a citizen of the Republic of France, residing at Paris, France, have invented 5 new and useful Improvements in the Making of Sheet Copper Electrolytically, of which the following is a specification.

It is well known that for electrolytically making sheet copper by means of a deposit 10 on a revolving cathode it has been proposed to use an anode constituted by a basket of any suitable shape partly surrounding the cathode and containing copper shavings or granulated black copper, such basket or container having its sides or walls, or only 15 such of them as are opposite the cathode, made of a porous material so as to form a diaphragm permitting the electrolyte to penetrate freely thereinto. Instead of being 20 porous the sides or walls may be holed, but in either case, when the manufacture of very long perfectly homogeneous and even sheets is attempted, such baskets or containers can not be made sufficiently large without being 25 coming deformed; and in consequence of the porous or holed wall opposite the cathode becoming deformed or warped, unevenness in the electrolytic deposit takes place, thus defeating the very purpose for 30 which said porous or holed walls are intended.

In industrial practice manufacturers have usually employed wood for the holed walls and this material is particularly liable 35 to warp.

A method intended to prevent the deformation of long elements, consist in constructing the basket or container with individual elements arranged side by side and 40 small enough to avoid deformation would be objectionable, since there would be at the jointing of two successive elements a zone wherein electrolysis would not take place under the same conditions as in the zone 45 corresponding to each of the elements and unevennesses in the cathodic deposit would ensue.

The same objection would be encountered when trying to use a single element 50 of adequate length reinforced with braces located in planes arranged at right angles to the axis of the cathode.

The improvement which is the object of 55 my invention meets the case and consists in using a single element of any required

length and in preventing any deformation of the said element by reinforcing it with braces set, not at right angles to the axis of the cathode, but slantwise with respect to said axis and so arranged that the action 60 resulting from the thickness of the said braces on the process of electrolysis will be felt uniformly on the whole surface of the revolving cathode, this arrangement of the braces constituting one of the characteristic 65 features of my invention.

In order that my invention may be more clearly understood I have illustrated, as an example, an embodiment of the latter in and by drawings appended hereto and 70 wherein:

Figure 1 is a plan view of apparatus arranged according to my invention, for making sheets of great length;

Figure 2 is a side view showing the arrangement of the various reinforcing braces of one of the holed walls;

Fig. 3 is a cross section of the apparatus.

1 is a vat containing the electrolyte into which are immersed the revolving cathode 80 2 and the anode. The latter consists of a basket or container 3, the walls or sides of which are porous or holed and in which are placed at 4 copper waste or granulated black copper. 85

Metal plates 5 supply the current to the anode and such plates are not immersed in the electrolyte but sprinkled with the electrolytic solution in the known manner so as to ensure good conductivity. 90

Figure 2 shows the device reinforcing the holed walls 3; each wall comprising two longitudinal braces 6 and 7 to which are secured the slanting braces 8 mentioned in the earlier part of this specification. Figure 95 2 shows the arrangement of these braces which are, as can be seen, slanting in respect to the axis of the cathode and suitably spaced, as illustrated, so that every cross plane always cuts, for one of the walls, one 100 brace 8 and can cut only one; the dotted lines a b, a' b' indicate clearly the arrangement required to fulfil this condition.

At their ends the longitudinal braces 6 and 7 are connected by normal uprights 9. 105

As will be easily understood, the rotation of the cathode and this characteristic arrangement of braces 8, will insure electrolytic action under the same conditions on all the cross planes (except at the ends of 110

the cathode) and I thus obtain the required reinforcing of the walls without impairing the homogeneousness and the evenness of the electrolytic deposit on the cathode.

5 Having now particularly ascertained and described the nature of my said invention as well as the manner in which the same is to be performed, I declare that what I claim is:

10 Apparatus for use in the electrolytic manufacture of copper sheets of substantial

size, comprising a container for the electrolyte a revolving cathode mounted in the container, and an anode serving as a container for copper waste or granulated black 15 copper and comprising permeable walls and reinforcing members mounted on said walls in a slantwise direction to prevent deformation of the said walls without impairing the evenness of the electrolytic deposit on 20 the surface of the revolving cathode.

MARCEL ANDRÉ JULLIEN.
